UNITED STATES PATENT OFFICE.

HERVEY H. MCINTIRE, OF SOUTH BEND, INDIANA.

PHOTOGRAPHIC-PRINTING MACHINE.

No. 856,716.

Specification of Letters Patent.

Patented June 11, 1907.

Application filed July 6, 1905. Serial No. 268,531.

To all whom it may concern:

Be it known that I, HERVEY H. MCINTIRE, a citizen of the United States, residing at South Bend, in the county of St. Joseph and State of Indiana, have invented new and useful Improvements in Photographic-Printing Machines, of which the following is a specification.

This invention relates to photographic printing machines and has for its object to provide a machine of this character that will print a number of photographs from the same negative and maintain a uniform exposure for each picture.

The details of construction, merits and advantages of my invention will be better understood by reference to the following description and to the accompanying drawings, in which:

Figure 1 is a front elevation of the machine with the platen raised and with part of the front of the case broken away to expose the interior mechanism, some of which are shown in section. Fig. 2 is an end elevation with the end of the case removed to expose the interior mechanism and showing in dotted lines the positions that the parts assume at different steps in the operation of the machine. Fig. 3 is a front elevation of the timing device. Fig. 4 is a plan view of Fig. 3. Fig. 5 is a detail plan view of the tilting frame that carries the electro-magnets showing in dotted lines one position of the parts in the operation of the machine.

Making renewed reference to the drawings, 1 designates a suitable case or cabinet which incloses the incandescent electric lamps 2 by which light is emitted to a negative 3 which may be positioned on a ground glass 4 that covers the opening 5 in the top of the case, the lamps being preferably mounted upon a shelf 6. To the top of the case and at the rear of the latter is hinged a platen frame 7 that carries a platen 8 which, when lowered, as by catching hold of the handle 9 at the front thereof, presses the photographic paper into intimate contact with the negative 3.

The electric lamps in the case are adapted to be automatically lighted and extinguished by the movement of the platen, the former action occurring upon the lowering of the platen and the extinguishment occurring when the indicator of the timing device has engaged with a terminal of an electric circuit.

The circuit for the electric lamps is shown as constituting a conductor *a* which leads in from the case at the rear as at 10 and then extends from the lamps to a contact terminal support 11 of an electric switch 12. The negative side *b* of the lamp lighting circuit terminates at the contact terminal support 13 of the switch and extends through the top of the case at 10.

The switch 12 consists of two carbon contact members 14 and 15 to which are secured terminal supporting clamping rings 11 and 13, the contact terminal 14 loosely sliding through an opening in a bracket 16 supported by a standard 17 in the lower end of which is slidably mounted a block 18 on which the terminal contact supporting ring 11 is mounted. Thus when the block 18 is lifted, it slides in the standard and carries with it the terminal support 11 and the terminal 15 and brings the latter into engagement with the contact terminal 14 which is also lifted with its terminal support 13 to the position shown in dotted lines in Fig. 2 and when in such position, the circuit is closed.

The elevating of the contact terminal 15 of the switch is controlled through the movement of the platen which is provided with an extension 19 that engages with the upper end of the push rod 20, which, at its lower end is pivoted to an arm 21 of a frame 22. The frame 22 is preferably U-shaped and pivoted at its lower end in a pair of ears 23 that extend upwardly from the bottom of the case. The end of the arm 21 straddles a post 24 on which is mounted a spring 25 that normally holds the end of the arm 21 upwardly and the frame 22 tilted rearwardly. The frame 22 carries a pair of electro-magnets 26 mounted on an end plate 27, and in this plate 27 is a pin 28 which projects through one side of the frame 22 within the path of a bell crank lever 29. One arm of this bell crank lever is slotted as at 30 and in this slot plays a stud 31 which is secured to the block 18 of the switch so that when the extension 19 on the platen depresses the rod 20 and tilts the frame 22, the pin 28 will engage the other arm of the bell crank lever 29 and tilt it in to the position shown in dotted lines in Fig. 2 elevating the first mentioned arm of said lever and lifting the block 18 and the contact member 15 of the switch into engagement with the contact member 14 of the switch, thus complet-

ing the circuit, and lighting the lamps. It will be noted that this action takes place immediately when the platen reaches its lowest position so that the photographic paper is, at 5 that time in the operation, held into intimate contact with the negative and light from the exterior is excluded.

The electro-magnets have a stationary core 32 secured to the frame 22 upon the side opposite to that through which the pin 28 projects and to this side of the frame is also secured a stationary armature 33 which is recessed to receive the ends of coiled springs 34 which bear against the magnets and normally hold them with their plate 27 up against the opposite side of the frame, in which position the pin 28 is projected through the opening in the frame. The circuit for the electro-magnet is entirely independent 10 of the electric lighting circuit and consists of a battery 35 from which extends the conductor *c* that terminates at the pointer of the timing device. The other side of the circuit is indicated at *d* and extends from the battery 15 through the coils of the electro-magnets and up to a binding post 36 on the indicator scale of the timing device. In order to close this circuit and energize the electro-magnets, the terminals which connect with the pointer 20 and scale respectively of the timing device must be connected and this is effected by the following mechanism: Extending from the top of the case is a board 37 on which is mounted a motor 38. This motor may be 25 mounted on the ordinary clock mechanism and on the arbor of the minute hand is frictionally mounted a pointer 39, the frictional engagement being such as to cause the arbor to carry the pointer around when the latter is not retarded by contact with an object. The board 37 also has a scale 40 thereon which is provided at one end with a pair of ears 41 which are pierced by a threaded rod 42. Mounted on this rod between the ears is a 30 thumb nut 43 by means of which the rod may be adjusted back and forth along and in alignment with the scale 40 so as to bring a contact member 44 on the inner end of the rod into any position on the scale, the said 35 contact member being engaged with the scale and located within the path of the end of the pointer 39, which, as it moves forward by the rotation of the arbor of the clock, will engage the contact member and complete the circuit for the electro-magnets, energizing the latter and causing them to be attracted toward their armature 33 against the tension of the springs 34; and during such movement they carry with them the 40 plate 27 which withdraws the pin 28 from engagement with the upright arm of the bell-crank lever 29 and permits the latter to fall forward to the position shown in full lines in Fig. 2 and the lower end of the lever is thus 45 lowered to break the electric lighting circuit

and also to restore the pointer to its normal position, which is out of engagement with the contact member 44. When the pointer is in its normal position as shown in full lines in Fig. 3 and in dotted lines at the left in Fig. 2, it is engaged with a stop pin 39^a. This restoration of the pointer is effected by a rod 45 which at its lower end is pivoted to the lower arm of the bell-crank lever and at its upper end it is bent at an angle toward the pointer 39; and, when the lower end of the lever 29 drops, the bent end of the rod engages with the edge of the recess or re-entrant portion 47 formed in the pointer and pushes the latter back to its normal position against the stop pin. When the bell-crank lever 29 is tilted to the position shown in dotted lines in Fig. 2, the bent end of the rod 46 is disengaged from the pointer and the latter is therefore permitted to be operated by the motor. Thus, the pointer serves as a switch for the electro-magnet circuit. There is a stop pin 39^a to limit the movement of the pointer 39 in one direction.

In order that access may be gained to the mechanism within the case, the front of the latter is preferably provided with a hinged door 48.

The operation may be briefly stated as follows. When the negative and photographic paper have been placed in position over the ground glass 4, the platen is lowered and when the extension 19 strikes the end of the rod 20, the frame 22 and lever 29 are tilted to the position shown in dotted lines in Fig. 2 raising the contact 15 of the switch and completing the lighting circuit and the light is thrown upon the negative to print the picture. Simultaneously with the upward movement of the lower arm of the bell crank lever, the bent end of the rod 46 is released from engagement with the pointer 39 and the latter is thus permitted to move from the position shown in full lines in Fig. 3 across the indication on the scale. When, however, the pointer engages the contact member 44, which has been previously adjusted to predetermine the exposure, the electro-magnetic circuit is completed and the magnets are energized causing them to be attracted toward the armature and withdrawing the pin 28 from engagement with one arm of the bell crank lever 29 and permitting the other arm of said lever to drop which breaks the electric lighting circuit and simultaneously lowers the rod 45 and causes its bent end to engage the edge of the recess 47 in the pointer and disconnects the pointer from the contact 44; thus insuring an accurate timing of the exposure of each picture. When the platen is again lifted and the push bar 20 released the spring 25 will force the arm 21 of the frame up and the frame will drop rearwardly in such position as to bring the pin 28 upon the opposite side of the up-

right arm of the bell crank lever, the pin being beveled upon one side to insure this movement.

Having thus fully described my invention 5 what I claim as new is:

1. In a photographic printing machine, a case, a lamp in the case, a switch, means for operating the switch to light the lamp, an electric circuit, a timing device to make and 10 break said circuit, and means in the circuit to release the switch operating means to extinguish the light.
2. In a photographic printing machine, a case, a lamp in the case, a switch, means for 15 operating the switch to light the lamp, an electric circuit, a timing device arranged to make and break the circuit, and an electro-magnet in the circuit adapted to release the switch operating means and extinguish the 20 light.
3. In a photographic printing machine, a case, a lamp in the case, a switch, means for operating the switch to light the lamp, an electric circuit, an electro-magnet in the circuit 25 adapted to release the switch operating means to extinguish the light, and a timing device controlled by the switch operating means and arranged to make and break the circuit of the electro-magnets.
4. In a photographic printing machine, a case, a lamp in the case, a switch to control 30 the lighting and extinguishing of the lamp, a timing device, an electric circuit having its terminals connected with the timing device, an electro-magnet in the circuit adapted to 35 be energized and de-energized by the timing device, means to operate the switch to light the lamps, said means being operated by the electro-magnets to release the switch and 40 extinguish the lamp, and means connected with the switch operating means to re-set the timing device and break the electric circuit.
5. In a photographic printing machine, a case having a lamp therein, and a switch to 45 control the lighting of the lamp, a platen, means operated by the platen to actuate the switch and light the lamps, a timing device, an electric circuit having its terminals connected with said timing device, an electro- 50 magnet in said circuit, means operated by the magnet to release the switch operating mechanism and extinguish the lamp, and means operated by the switch operating means to re-set the timing device and there- 55 by break the circuit of the magnets.
6. In a photographic printing apparatus, a case having a lamp therein, a switch to make

and break the circuit for the lamp, a tilting frame, an electro-magnet carried by the frame, a switch operating lever movable with 60 the frame of the electro-magnets, means for tilting the frame and the switch lever to close the circuit for the lamps, and a timing device having terminals for the electro-magnet circuit and adapted to complete said circuit and 65 release the switch operating lever, substantially as specified.

7. In a photographic printing machine, a case having a lamp therein and a switch for controlling the lighting and extinguishing of 70 the lamp, a platen, a tilting frame, a switch operating lever movable with the frame, means operated by the platen to tilt the frame and the lever and complete the circuit for the lamps, an electro-magnet carried by 75 the tilting frame, and means for energizing said magnets to release the switch operating lever from the frame, substantially as specified.

8. In a photographic printing machine, a 80 case having a lamp therein, a switch to control the lighting and extinguishing of the lamp, a frame pivoted in the case, a switch operating lever pivoted in the case, an electro-magnet carried by the frame, and having 85 a pin normally held projected in the path of the switch operating lever, whereby the latter is moved with the frame to complete the lighting circuit, and means operated by the platen to tilt the frame. 90

9. In a photographic printing apparatus, a case having a lamp therein, a switch for controlling the lighting and extinguishing of the lamp, a frame pivoted in the case, an electro-magnet mounted in the frame, a plate secured to the end of the magnet, a pin secured to the plate and projecting through the frame, a bell-crank lever having one arm engaged by said pin and the other arm connected with the switch to operate the latter, a rod connected with the tilting frame, and a hinged platen to engage the rod, tilt the frame, lift the lever and connect the contacts of the switch, and a timing device adapted to complete the circuit of the electro-magnet 105 and retract the pin from engagement with the bell-crank lever. 100

In testimony whereof I affix my signature, in presence of two subscribing witnesses.
